FLEXIBLE CIGARETTE CASE WITH REINFORCING MEANS

Filed Sept. 22, 1944

UNITED STATES PATENT OFFICE

2,438,408

FLEXIBLE CIGARETTE CASE WITH
REINFORCING MEANS

John A. Mace, Tampa, Fla.

Application September 22, 1944, Serial No. 555,310

1 Claim. (Cl. 206—41)

1

The present invention relates to improvements in protective attachments for cigarette cases and refers more particularly to a (crush-proof) leather cigarette case.

An object of the invention is to provide a device so constructed and arranged as to admit of its insertion into a conventional leather cigarette case for converting such case into armored compartments adapted to withstand pressure and avoid the crushing or mashing of the cigarettes.

Another object of the invention is to produce a simple and economical form of attachment adapted for placement in any standard form of cigarette case to reinforce and render rigid the walls of the case, which are ordinarily flexible, to the end that adequate protection may be given to the cigarettes to avoid crushing of the same which is desirable from a smoker's standpoint.

A still further object of the invention is to so construct and arrange a duplex attachment for the twin pockets of a foldable flexible cigarette case that when folded the rigid walls of the attachment are exterior of the two cigarette pockets of the case in such relation that such walls provide an overall rigid protection for the contents of such pockets.

With the foregoing and other objects in view the invention will be hereinafter more fully described and more particularly pointed out in the appended claim.

In the drawings:

Figure 1 is a perspective view, with parts broken away and parts shown in section, of a conventional leather cigarette case having the improved attachments applied therein;

Figure 2 is a perspective view of the two elements of the device shown in separated and disassembled relation;

Figure 3 is a longitudinal section taken on the line 3—3 of Figure 1 with the case folded;

Figure 4 is a transverse section taken on the line 4—4 of Figure 1;

Figure 5 is a perspective view of a modified form of plate, and

Figure 6 is a similar view of a modified form of distending unit.

Referring more particularly to the drawings 10 designates generally a flexible or leather cigarette case of a conventional construction which is foldable along a transverse center line indicated by the line 4—4 in Figure 1 for which purpose a single thickness of the leather or other flexible material exists at this zone. The two pockets or compartments for the cigarettes are

5 indicated at 11 and 12, these pockets being closed on all sides save toward the central flexible hinging or folding portion where they have open mouths to receive cigarettes which are placed therein in the manner indicated in Figure 4.

In accordance with the present invention I equip each pocket of such cigarette case with a protective device consisting of the two elements shown in Figure 2.

10 One such element comprises a plate 13, preferably of rigid or substantially rigid material, for instance a metal plate, advantageously of aluminum. Three of the edges of such plate are formed with flanges 14, 15 and 16. The plate 13 is of substantially the same dimensions of a cigarette pocket of the case and is adapted to be slid in through the open mouth of the same with the flange 14 leading. The flat edge 17 of the plate 13 is toward the open mouth of the cigarette pocket. The flanges 14 and 16 are turned outwardly from the plane of the plate 13 only a small angular distance so that said flanges are diagonal rather than perpendicular to the plane of said plate 13.

15 The second element of the protective attachment consists of a device having three members 18, 19 and 20. These members have a height substantially of the diameter of the cigarettes and such device is adapted to be slid into the cigarette pocket alongside the plate 13 on that side of the plate from which the flanges are struck up so that the member 18 engages against the flange 14 of the plate and the members 19 and 20 against the side flanges 15 and 16, respectively.

20 The members 18, 19 and 20 distend the walls 11 and 12 of the pockets and hold such pockets open and against collapse and in this manner such distending devices cooperate with the plate 13 which forms an extensive armor for the pocket against external pressures.

25 The distending device is preferably composed of resilient strip metal in which two of the strips are overlapped and riveted or otherwise secured together to constitute the basic member 18 and to neutralize the inherent spring action of the material. Both the lateral members 19 and 20 are free to move under this inherent resiliency which is aided by the fact that such members 30 are unattached at their outer ends which extend at the mouth of the pocket. The lateral members 19 and 20 are given a set or bias in which they diverge from the central member 18 whereby when the device is inserted into a pocket of the case the side members 19 and 20 will be shifted

inwardly by the side edges of the pocket and by the flanges 15 and 16 of plate 13. This will place the device under tension and this tension will also be communicated to the plate 13 so that the device as a whole, consisting of both elements, will be frictionally held in the pocket and prevented from readily escaping therefrom.

The outer corner portions, or the corner portions of the plate 13 at the mouth of each pocket are rounded or beveled off or cut away, as indicated at 21, to avoid the presentation of sharp corners which might otherwise chafe and cut the leather of the case, particularly in the hinging action thereof.

In the use of the device, as many of the units consisting of a plate 13 and distending devices 18, 19, 20 are utilized as there are pockets in the case. In the case of a twin pocket leather cigarette holder, two such devices are employed with the two plates 13 placed in the bottoms of the two pockets 11 and 12 when the case is laid out flat in the open position, as shown in Figure 1; and the two distending devices are fitted in the pockets on top of the plates 13. This order and relationship causes the two plates 13, when the case is folded, as illustrated in Figure 3, to exist as an armor protecting substantially the entire overall external area of the case. Moreover the flanges of the plates mutually turn inwardly, as also shown in Figure 3, so that the left edge of the case in Figure 3 is also protected by these flanges. The members 18, 19, 20 also hold the plates apart and the pockets distended. The two plates and the two distending devices thus cooperate in a two-pocket cigarette case to form substantially closed compartments for cigarettes protected from crushing on two sides.

Referring more particularly to Figure 5 a modified form of plate 13^a is shown having one or more strengthening grooves 25 of sufficient depth to add strength to the plate. This construction presents a groove on the inner side of the plate which is presented to the cigarette and a rib on the outer side of the plate. Such construction makes the plate more rigid especially at the inner end where it lacks the support of the distending element composed of the members 18, 19 and 20 when the cigarette case is in the closed position as shown in Figure 3.

Referring more particularly to Figure 6, a modified form of distending device is shown at 18^a,

19^a and 20^a in which all of these parts are continuously formed of the same band of metal, integral throughout and of the same gage and width. In such case the double thickness of the parts at 18 in Figure 2 may be eliminated while the same strength is secured by adding a groove and rib construction 26 to the bar 18^a. This groove and rib forms a strengthening strip 18^a. The device of Figure 6 accomplishes the same purpose as the part 18 in Figure 2 and at the same time eliminates unnecessary weight and material. The distending devices of Figures 2 and 6 are optional means of neutralizing the spring action of the material.

15 I claim:

20 In combination with a flexible cigarette case having a pocket, a removable protective attachment comprising a substantially rigid plate having diagonal flanges extending upwardly from three edges thereof with the other edge flat and adapted to be slid into the pocket of the cigarette case with the flat edge toward the open mouth of the pocket, and a distending device associated with the said plate and consisting of three side members and an open side, two of the side members having their outer edges unsupported at the outer side and being resilient and flexible and given an outward bias diverging from one another, said device adapted to be slid into the pocket of said cigarette case on said plate and with the members of the device engaging the flanges of the plate, said members being substantially of the height of the thickness of a cigarette, said outwardly sprung members adapted to frictionally bind in the pocket of the case.

35 JOHN A. MACE.
